CLAIM

The ornamental design for a printer access door, substantially as shown and described.

DESCRIPTION

FIG. 1 is a perspective view of a printer access door in accordance with the present invention;

FIG. 2 is a front elevational view thereof;

FIG. 3 is a top plan view thereof;

FIG. 4 is a right side elevational view thereof; and,

FIG. 5 is a left side elevational view thereof.

The broken lines in FIGS. 1-5 are for illustrative purposes only and form no part of the claimed design.
